JOHN F. HOTTMAN, OF CHICAGO, ILLINOIS.

BOILER AND THE LIKE.

Application filed June 7, 1924. Serial No. 718,439.

This invention has to do with certain improvements in boilers. It has to do particularly with improvements in locomotive boilers, but is also applicable to other boiler constructions of relatively large size. In general, my improvements relate to all internally fired steam boilers which have essentially a rectangular fire box, and are commonly known as locomotive type boilers, and 10 said improvements pertain especially to locomotive boilers, but I do not intend to limit the same to this type of boiler. In describing the invention I will in my description of the same deal with and make use of locomotive boilers merely for the purpose of setting forth my improvements more clearly.

Locomotive boilers for some years past and at the present time have reached the clearance limits of the railways in so far as width 20 of fire box and diameter of the barrel of the locomotive boiler is concerned. The only increase in size and capacity possible is in the length of the barrel. This increase in length of barrel causes an abnormal length of the 25 flues or fire tubes of the boiler. This abnormal flue length in the barrel has brought about serious defects to the front part of the barrel and the flues in this part of the boiler, notably pitting and corrosion of these parts, 30 all of which is caused by lack of heat in the forward part of the barrel of large and long locomotive boilers. This has caused a non-release of the steam bubbles to the surface of the water line, causing general sluggish action 35 in the forward part of the barrel, causing injurious matter to be trapped in the water which attacks the material of the boiler. In addition, this sluggishness of the water in the front part of the locomotive 40 boiler barrel results in considerable loss of the heat generated in the fire box.

The above failings have to some extent been recognized and combustion chambers have been added to the locomotive fire boxes. 45 However, the deficiencies of the long locomotive barrel have not been overcome nor has the premature wasting away or failing of the tubes or flues and the boiler shell in the forward part of the locomotive boiler barrel been relieved. As a consequence, the users of 50 large numbers of locomotive boilers have been put to great expense for repairs, replacement of boiler parts and material, and to fuel losses for which no adequate return is 55 received. On the contrary, the addition of a

combustion chamber to a fire box adds a large burden to the first cost of the locomotive boiler and subsequently adds a heavy burden for maintenance charges in order to keep the locomotive boiler in serviceable condition. 60

All of the above is brought about by the large number of stay bolts necessary to apply a combustion chamber properly and safely to any locomotive fire box. Furthermore, the application of a combustion chamber to the 65 locomotive fire box brings the combustion chamber into the rear end of the cylindrical boiler barrel, which cylindrical course is self-sustaining by itself. The application of a combustion chamber which extends into the 70 rear end of the cylindrical boiler barrel and is connected thereto by large numbers of screw stay bolts sets up stresses which are difficult to locate or define, although the fact that they are ever present is always evident 75 from the cost of maintaining this part of the locomotive fire box in active service.

According to the present invention, I provide a combustion chamber separate and distinct from the fire box itself and locate the 80 same at or near the center of the boiler barrel at which point it is properly supported with respect to the boiler barrel. I also provide flues or fire tubes of comparatively large size leading from the front end of the fire box 85 into said combustion chamber; so that some of the flaming gases can reach through these flues or tubes of large size and directly into said combustion chamber. Consequently, a large portion of the flaming gases reach the 90 center of the boiler barrel with a relatively small drop of heat from the temperature in the fire box.

This is not the case with the previous type of locomotive boiler combustion chamber 95 which constitutes in effect merely a direct forward extension from the front end of the fire box; since this previous construction gives only a very small length of flame travel—normally from three to six feet—and when the flame gases strike and enter the very small tubes and flues previously used, the flames of said gases are extinguished to a large extent and sometimes entirely. Thus it will be seen that the large body of water 100 in the locomotive barrel is not properly heated because of the reduced or extinguished gas flames, and the burden of work of producing steam in previous constructions has fallen to an abnormal degree on the loco- 110

motive fire box. Since the water surrounding this fire box constitutes only a small part of the water contained within the locomotive boiler barrel, and since this water surrounding the fire box is limited in its ability to absorb the great amount of energy produced, say by coal burning at the rate of one hundred and ten pounds per hour per square foot of grate surface, a furnace effect is produced which generally results in a leaky fire box and makes it necessary to renew the fire box long before its time. All this causes loss in coal, material and revenue of the locomotive when premature renewals are made to the fire box.

With my improved arrangement of flame flues and combustion chamber reaching approximately to the center of the locomotive boiler barrel, the flaming gases exert their maximum effect where the largest bulk of water is present, thus relieving the fire box of the large burden of the work to be done, namely, production of steam.

My improved construction of boiler, by bringing the flaming gases approximately to the center of the boiler barrel, reduces the length of the flues or tubes in the extreme forward section of the barrel to a length which is more efficient than an extremely long flue in the diameters as universally used in locomotive boilers. Approximately the flues or tubes in the front part of the barrel will be from thirty to fifty diameters in length based on the type of flue or tube used, and the standard flues will be approximately from seventy to eighty-five diameters in length. This will raise the water to high temperature in the forward part of the locomotive boiler barrel and will cause better circulation, thus removing the cause of pitting and corrosion that is so prevalent in the extremely long locomotive barrels, and which is found almost altogether in the flues, shell and forward flue sheet in the barrel.

My improved boiler construction is a steam generator throughout the whole length of the locomotive boiler barrel instead of being a preheater of the water at the forward end as is the case with previous types of construction. Also my improved boiler construction will give a slightly larger water content to any given size of locomotive boiler barrel, a more efficient heating surface, and a reduction of fifteen hundred to two thousand pounds in weight on axles for an average of the present locomotive boiler as found in use at this time.

Reference may now be had to the drawings in which:

Figure 1 shows a section through one construction of boiler embodying the features of the present invention, there being a number of different sizes of flues or tubes between the fire box and the combustion chamber;

Figure 1^a shows a horizontal section on

the line 1^a—1^a of Figs. 1 and 2, looking in the direction of the arrows;

Fig. 2 shows a cross section taken on the line 2—2 of Fig. 1, looking in the direction of the arrows;

Fig. 3 shows a cross section on the line 3—3 of Fig. 1, looking in the direction of the arrows;

Fig. 4 shows a cross section on the line 4—4 of Fig. 1, looking in the direction of the arrows;

Fig. 5 shows a cross section on the line 5—5 of Fig. 1, looking in the direction of the arrows;

Fig. 6 shows a longitudinal section corresponding to that of Fig. 1, but shows a modified form of construction;

Fig. 7 shows a fragmentary section on the line 7—7 of Fig. 6, looking in the direction of the arrows;

Fig. 8 shows a fragmentary section on the line 8—8 of Fig. 6, looking in the direction of the arrows, but illustrating and embodying another flue or tube arrangement;

Fig. 9 shows a fragmentary longitudinal section through another modified form of construction;

Fig. 10 shows a cross section on the line 10—10 of Fig. 9, looking in the direction of the arrows;

Fig. 11 shows a fragmentary longitudinal section through another modified form of construction; and

Fig. 12 shows a fragmentary longitudinal section on enlarged scale illustrating the attachment of a flue or tube to the flanged out portion of the flue sheet of the construction of Fig. 11.

Referring first to the construction shown in Figs. 1, 1^a, 2, 3, 4, and 5, the boiler therein illustrated includes the barrel or shell 15 which is built up from the sections 16, 17 and 18. The section 18 is preferably of larger size than the section 16, the intermediate section 17 being conical, so that the top and bottom portions of the section 18 stand respectively higher and lower than the top and bottom portions of the section 16.

At the rear end of the boiler is the fire box 19, the same being located within the section 20. This section, as shown in Fig. 2, is of the usual inverted U-shape. It includes the outer and inner shells 21 and 22 respectively, the shells being separated in their top and side portions so as to establish the continuation chamber which includes the water-legs 23 and 24. The mud-ring 25 closes the lower portion of the space between the plates 21 and 22. The smoke box 26 is formed at the front end of the shell in accordance with standard practice.

All of the foregoing is in accordance with standard practice in locomotive boiler construction. It is also the customary practice at the present time to place a flue sheet 27

at the front end of the boiler section 16 and another flue sheet at the front end of the fire box 19, and then to extend the fire flues or tubes the entire distance continuously between these flue sheets. It has also been previous practice to extend the front portion of the fire box forwardly a substantial distance within the section 18 so as to establish a combustion chamber and thus place the flue sheet thereof closer to the flue sheet 27.

According to the present invention, I place a flue sheet 28 at or adjacent to the front end of the fire box, or at the front end of the extended combustion chamber, if one is used, and I then place a combustion chamber 29 between these flue sheets, and substantially half way between them. This combustion chamber 29 is in turn provided with front and rear flue sheets 30 and 31, and I provide a series of flues or tubes between the flue sheet 28 at or adjacent to the front end of the fire box and the flue sheet 31, and another set of tubes or flues between the flue sheet 30 and the flue sheet 27 which is at the front end of the boiler and near the smoke box. These I will designate as the rear and front sets of flues respectively.

Ordinarily the flues or tubes of the rear set will be of larger size relatively than those of the front set although this is a matter of option in design. In any case, however, the rear set of flues or tubes constitute fire flues of sufficient size to pass the flames without extinguishing them, so that said flames are delivered through the rear set of flues and into the combustion chamber 29 and may redistribute within said combustion chamber and enter the flues or tubes of the front set in redistributed condition and flow there-through under conditions of flow established by the relative lengths of the flues or tubes of the front set as compared to their diameters.

From the above it is apparent that with a boiler of given overall dimensions between the flue sheets 28 and 27 the actual lengths of the individual flues or tubes will ordinarily be less than one-half the actual distance between the flue sheets. For this reason, the overall length of the boiler may be very materially increased without increasing the ratio of length to diameter of the flues or tubes; or on the other hand if it is unobjectionable to maintain a certain ratio of length to the diameter of flues or tubes, the overall length of the boiler may be very materially increased without seriously increasing the obstruction to the flow of gases or reducing the average steaming capacity per square foot of flue or tube surface, and in any case, the rear set are fire flues or tubes to deliver the flames to the combustion chamber.

In the particular construction illustrated, the combustion chamber 29 is a pressure sustaining barrel of corrugated steel having a

flanged head riveted to each end. These heads constitute the flue sheets 30 and 31, already referred to.

The weight of flues or tubes, combustion chamber and superheater units if used, may be supported in any convenient manner, as, for example, by the use of sling stays 32 and 33, suspended from suitable brackets 34 and 35 on the top portion of the barrel section 17, the stays 32 and 33 being pinned to the yokes 36 and 37 which are in turn screwed or otherwise secured into the corrugated shell.

Ordinarily there will be provided a relatively large flame flue 38 reaching between the lower portion of the flue sheet 28, and the lower portion of the flue sheet 31. This relatively large flame flue 38 should be of sufficient size to pass a large part of the flame; and incidentally to allow a workman to pass through into the combustion chamber 29 during construction or repair. Preferably also this flame flue 38 is made of corrugated sheet steel and riveted to flanges of the flue sheets 28 and 31 respectively.

Extending between the flue sheets 28 and 31 is a group of flues or tubes which occupy practically the entire space available so as to secure the maximum amount of gas carrying capacity. These flues or tubes may be of equal or different sizes, and in the construction of Figs. 1, 1^a, 2, 3, 4 and 5, I have illustrated two sizes of flues or tubes designated 39 and 40. This arrangement is desirable in many ways, but under some circumstances it will be found preferable to make the flues or tubes all of the same size, as shown for example in the modifications illustrated in Figs. 8 and 9.

In the construction of Figs. 1, 1^a, 2, 3, 4 and 5, the flue sheet 28 is set into an intermediate section 41 which has its edge portion flanged and riveted into the front edge of the fire box sheet 22 which is largely in accordance with present practice.

Referring to Figs. 2, 3, 4 and 5 in particular, it will be noted that the position of the combustion chamber 29 is such that the lowermost flues or tubes leading forwardly therefrom will properly enter the flue sheet 27 at the smoke box end; and it is also observed that the size of the combustion chamber 29 is such that the upper flues of both the front and rear sections will come into proper position with respect to the upper portion of the fire box and combustion chamber. Furthermore, the combustion chamber 29 should preferably be of such size and shape that it can be readily set into place through the opening in the front portion of the fire box, thus facilitating construction.

It may, therefore, be stated that the diameter of the combustion chamber 29 should be such as to be included within the top portion 42 of the fire box sheet 28 or 50^a, and the lower portion as defined by the position of the

lower portion of the circle of the front flue sheet 27. These facts are readily apparent from an examination of Figs. 2 and 3 in particular. The flue space occupied by the front and rear groups of flues or tubes which are connected into the combustion chamber 29 does not occupy a portion of flue sheet at each side of this area. This fact is apparent from Figs. 2, 3, 4 and 5, wherein are observed the groups of side flues or tubes 43 and 44 respectively. The flues or tubes of these two groups reach directly between the front and rear flue sheets at the extreme ends of the flue or tube section of the boiler and extend past the position of the combustion chamber 29.

In the modified construction of Figs. 6, 7 and 8, the flue sheets 45 and 46 at the front and rear ends of the combustion chamber 29 are set against intermediate rings 47 and 48, the ends of the combustion chamber itself being flanged outwardly and then all parts drawn together by through rivets. The upper portions of the rings 47 and 48 reach considerably above the upper edges of the flue sheets 45 and 46, so as to take the sling stays 49 and 50 by which the structure is held in place.

In the modified construction of Figs. 9 and 10, the flues or tubes 49 of the rear section are all of the same size with the exception of the lowermost flame flue 38 which is of larger size.

In the modified construction of Figs. 11 and 12, the front portion of the fire box is closed directly by a single sheet 50^a which has its edge portion flanged and set directly into the fire box sheet 22 as will be clearly evident from Fig. 11. That is to say, use of two sections has been eliminated and the front fire box section and the tube sheet are a single structure.

Furthermore, in Fig. 12, I have shown the flue sheet as being flanged outwardly to establish the circular flanges 51 into which are set the end portions of the flues or tubes 52. The parts are then joined together by rivets 53 which are countersunk into the flues or tubes so as to eliminate any obstruction to the flow of flame and gases. I have illustrated the usual steam dome 54 in the boiler section 17 and above the position of the combustion chamber 29.

It will be noted that in each instance, the combustion chamber is of substantially larger cross sectional area than that of either group of flues or tubes. Furthermore, the combustion chamber is of substantial volume as compared to volume of gases contained within either group of flues or tubes. As a consequence, the intermittent pull, due to the intermittent nature of the locomotive draft created by the cylinder exhausts, will be largely equalized within the combustion chamber, and also within relatively large flues or tubes of the rear group, so that a

much more uniform pull of draft will be exerted on the bed of coals in the furnace.

While I have herein shown and described only certain embodiments of the features of my present invention, still I do not intend, to limit myself to the same, except as I may do so in the claims.

I claim:

1. In a steam boiler, the combination with the fire box and the flue sheet at the front end of the same, together with the flue sheet at the front end of the boiler, of a cylindrical combustion chamber within the barrel of the boiler between said flue sheets, flue sheets at the front and rear ends of said combustion chamber, a series of large flues or tubes reaching from the fire box flue sheet to the rear combustion chamber flue sheet, including a flame flue of relatively larger size, a series of flues or tubes reaching from the flue sheet at the front end of the combustion chamber to the flue sheet at the front end of the boiler, and a series of straight flues or tubes reaching from each side portion of the fire box flue sheet directly forward to the side portions of the flue sheet at the front end of the boiler and extending directly past the side portions of the combustion chamber, substantially as described.

2. In a steam boiler, the combination with the fire box and the front flue sheet thereof, together with the flue sheet at the front end of the boiler, of a combustion chamber within the barrel of the boiler between said flue sheets, flue sheets at the front and rear ends of said combustion chamber, a series of fire flues or tubes reaching from the fire box flue sheet to the rear combustion chamber flue sheet, a series of flues or tubes reaching from the flue sheet at the front end of the combustion chamber to the flue sheet at the front end of the boiler, and a series of straight flues or tubes located at one side of the combustion chamber and reaching directly from the fire box flue sheet forwardly to the flue sheet at the front end of the boiler, substantially as described.

3. In a steam boiler having an integrally constructed fire box in its rear portion, together with a series of straight flues or tubes extending longitudinally of the boiler directly from the front sheet of the fire box to the front flue sheet of the boiler, a combustion chamber within the barrel of the boiler, a series of flues or tubes extending longitudinally from the fire box to the rear end of the combustion chamber, and a series of flues or tubes extending longitudinally from the front end of the combustion chamber to the front end of the boiler, substantially as described.

4. In a steam boiler having a fire box of the locomotive type and a forwardly extending cylindrical barrel, a flue sheet at the front end of the firebox, a flue sheet at the front end of the barrel, a group of flues or tubes

- reaching forwardly from the firebox flue sheet and substantially embraced within the circle whose diameter has one terminus defined by the top or highest point of the firebox, and its 5 other terminus defined by the bottom and lowest point of the flue sheet at the front end of the boiler barrel, a cylindrical combustion chamber of any desired length within the barrel of the boiler having a diameter substantially 10 the same as that just defined, the group of flues or tubes aforesaid reaching from the firebox flue sheet into said combustion chamber, another group of flues or tubes embracing a similar area reaching from the 15 combustion chamber to the front boiler flue sheet, and a group of straight flues or tubes outside of the area so defined reaching directly from the firebox flue sheet forwardly to the flue sheet at the front end of the boiler 20 and past the combustion chamber, substantially as described.
5. In a steam boiler having a firebox of the locomotive type and a forwardly extending cylindrical barrel, a flue sheet at the 25 front end of the firebox, a flue sheet at the front end of the boiler, a group of flues or tubes reaching forwardly from the firebox flue sheet and embraced within a smaller area than the area substantially embraced within the circle whose diameter has one terminus defined by the top or the highest point of the firebox, and its other terminus defined by the bottom and lowest point of the flue sheet at the front end of the boiler barrel, a cylindrical combustion chamber of any desired length within the barrel of the boiler and having an area substantially the same as the smaller area just defined, said group of flues or tubes reaching from the firebox flue sheet into said combustion chamber, another group of flues or tubes embracing a similar area reaching from the combustion chamber to the front boiler flue sheet, and a group of straight flues or tubes outside of the area so defined reaching directly from the firebox flue sheet forwardly to the flue sheet at the front end of the boiler, substantially as described.

JOHN F. HOTTMAN.
